UNITED STATES PATENT OFFICE.

CURTIS L. CRUVER, OF CHICAGO, ILLINOIS.

DESIGN FOR A MIRROR.

No. 40,148.

Specification for Design.

Patented July 20, 1909.

Application filed January 24, 1907. Serial No. 353,908. Term of patent 7 years.

To all whom it may concern:

Be it known that I, CURTIS L. CRUVER, a citizen of the United States, residing at Chicago, in the county of Cook and State of Illinois, have invented a new, original, and ornamental Design for Mirrors, of which the following is a specification, reference being had to the accompanying drawing, forming part thereof.

The figure is a perspective view showing a mirror embodying my new design.

I claim:—

The ornamental design for a mirror as shown.

CURTIS L. CRUVER.
